UNITED STATES PATENT OFFICE.

FRED D. ACKERMAN, OF HAMPTON, VIRGINIA.

SLIDING DOOR FOR RAILWAY-CARS.

No. 811,115.

Specification of Letters Patent.

Patented Jan. 30, 1906.

Application filed July 28, 1905. Serial No. 271,685.

To all whom it may concern:

Be it known that I, FRED D. ACKERMAN, a citizen of the United States, residing at Hampton, in the county of Elizabeth City and State 5 of Virginia, have invented certain new and useful Improvements in Sliding Doors for Railway-Cars, of which the following is a specification.

My invention relates to sliding doors principally for railway-cars.

The object of my invention is to provide means whereby double sliding doors may be opened and closed together when either one is operated.

15 My invention will be more fully understood by having recourse to the drawings forming a part of this specification, in which—

Figure 1 is an end view of the car, having its upper part removed, also the inside casing 20 cut away, to show my invention in position. Fig. 2 is an end view of the upper portion of the doors. Fig. 3 is an end view of the H-shaped track and the flanged rollers. Fig. 4 is a perspective view of the upper rack-bar. 25 Fig. 5 is a perspective view of the lower rack-bar.

In the drawings like reference-numerals indicate similar parts in all the views.

1 is the car-body, and 2 is an end of the 30 same, upon which is placed the hereinafter-described mechanism.

3 and 3^A are sliding doors which open from each other, and when so open they are concealed behind the ceiled portion of the car. 35 woodwork. The doors are adapted to open together when either 3 or 3^A is operated.

Upon the upper portion of the doors there are placed rack-bars 4 and 5, having plate portions 6 and 6^A, respectively, for fastening 40 them to the doors in a suitable manner. These plates cause the rack-bars to have an L-shaped form and are placed above the doors, as shown in Figs. 1 and 2. The plates 6 and 6^A are placed above the doors at their 45 centers, so that they may be properly balanced. The plate 6^A is provided with an offset for permitting the rack-bar 4 to pass it, as shown. The rack-bars have also an angular or L shape, as shown in Figs. 3 and 5, with 50 the teeth arranged in a suitable manner upon one of the arms of the angle, and when the racks are in place upon the doors the teeth are oppositely disposed, as shown.

7 is a gear-wheel meshing with and operating 55 both racks in opposite directions, so as to place the doors in the positions shown in Figs.

1 and 2, which is also indicated by the arrows at the upper portions of both figures.

The gear-wheel 7 rotates upon the shaft or axle 8, located upon the end woodwork of the 60 car.

In order to prevent the gear-wheel 7 from getting out of mesh with the racks due to vibration, I provide rollers 9 and 10, which roll upon the toothless portions of the rack-bars and are fastened, together with the gear-wheel 7, to the base-plate or support 10^A.

To properly hang the doors and to eliminate friction, I also provide rollers 11, having deep double flanges 12 thereon, two of which 70 are usually placed near each end of the upper portion of the doors one above the other at such a distance apart so as to enable them to receive the double-flanged or H-shaped track or hanger 13 between them, as shown in Fig. 4. 75

The rack-bar 4 acts, as shown in Fig. 3, so as to prevent the gear-wheel or pinion 7 from becoming disconnected from the rack by the plain edge bearing against the pinion should the rollers 11 become inoperative or leave 80 their track.

The rollers 11 are supported upon shafts or axles 14. Also the rollers 9 and 10 have similar axles, (denoted by 15,) which are fixed in the base-plate 10^A. 85

By my invention I am enabled to provide means whereby the "hanging" or disarrangement of car-doors is prevented, as the mechanism is such that the parts work easily and are not liable to get out of order. 90

Having described my invention, what I claim, and desire to secure by Letters Patent, is—

1. In a device of the class described, the combination with double sliding doors, of plates fastened at the middle upper portion of said doors and having rack-bars of an L-shape cross-section and disposed at right angles to said plates, and rotary means for reciprocating said racks. 95

2. In a device of the class described, the combination with double sliding doors, of plates or webs secured to the doors of less width than the same and disposed at the center thereof, said plates or webs having rack-bars of L shape in cross-section and at right angles to the plates or webs, a gear-wheel between the racks adapted to reciprocate the same to open and close the doors together, rollers on one side of the doors, and independent H-shaped tracks for the rollers, one for each of the said doors. 105 110

3. In a device of the class described, the combination with double sliding doors, of a plate or web secured to the top of each door near its center, a rack-bar on each plate at 5 right angles thereto extending above and beyond the said doors, a pinion between the racks for opening and closing one door by the other, one of the said rack-bars extending upon each side of the pinion, rollers on the plain surface 10 of the racks for preventing vertical movement thereof, flanged rollers on each side of

the doors, and tracks or guide-rails having an H shape in cross-section for supporting said rollers.

In testimony whereof I have hereunto affixed my signature, in the presence of two witnesses, this 19th day of July, 1905.

FRED D. ACKERMAN.
